UNITED STATES PATENT OFFICE.

WILLIAM E. WINE, OF TOLEDO, OHIO.

HOPPER-CAR CONSTRUCTION.

Application filed January 30, 1926. Serial No. 84,970.

My invention relates to railway car hopper construction and more particularly to a hopper car door frame unit and the mode of combining the latter with the chute plate and side plates of a hopper and with the door for closing the lading discharge opening. The principal object of the invention is to strengthen and simplify car hoppers and to provide structural means which ensure that the doors shall efficiently and reliably function.

A primary feature of the invention consists in providing an inclined hopper having downwardly converging sides with a cargo discharge opening of substantially rectangular form, and in associating therewith a substantially rectangular hinged door for closing said opening.

A further feature of the invention consists in providing a car hopper door frame with a cargo discharge opening which is bounded by outwardly projecting sealing flanges, and in combining therewith a substantially rectangular hinged door having an inwardly projecting sealing flange for cooperating with the corresponding flanges of the frame.

Another feature of the invention involves a car hopper door frame having a discharge opening and provided with outwardly projecting sealing flanges adjacent the sides and lower edges of said opening, and in combining therewith a hinged door having inwardly projecting sealing flanges for cooperating with the flanges of the frame, the flanges at the sides of the discharge opening being tapered so as gradually to increase in height toward the lower edge of the opening.

A still further feature of the invention consists in the provision of a hopper car door frame of substantially trapezoidal form having a rectangular discharge opening.

Other features of the invention, residing in advantageous combinations of parts and details of construction, will hereinafter appear.

In the drawings illustrating a preferred embodiment of the invention, the scope whereof is pointed out in the claims—

Figure 1 is a plan view of a railway car hopper embodying the invention.

Figure 2 is a side elevational view of the construction shown in Fig. 1, a well known form of door locking mechanism for retaining the doors of the hopper in closed position being indicated in dotted lines.

Figure 3 is an end elevational view of the hopper construction.

Figure 4 is a detail elevational view of the door frame unit illustrating the preferred construction.

Figure 5 is a plan view of the door frame unit, and

Figure 6 is a side elevation thereof.

Figure 7 is a sectional view on the line 7—7, Fig. 4.

Figure 8 is a detail sectional view on the line 8—8, Fig. 4.

The general form of hopper illustrated in the drawings for the purpose of explaining the invention is well known; but it is to be understood that the particular configuration shown in the drawings is not essential, as modifications in the form of the hopper may obviously be made without departing from the scope of the claims defining the invention.

The hopper comprises an inclined bottom or chute plate 1 and sides 2 which customarily are formed of metal. The sides of the hopper converge downwardly and each is provided along its lower edge with an inwardly extending flange 3 which lies beneath and is riveted to the inclined bottom plate 1. The converging sides 2 of the hopper are, in the present instance, both inclined to the vertical, their lower segments being somewhat more steeply inclined.

Rigidly secured to the bottom plate 1 and side sheets 2 at the discharge end of the hopper, as by means of rivets, is a door frame 4 which may be formed as a steel casting. The door frame is preferably of substantially trapezoidal form and may advantageously be provided at its opposite sides with inwardly extending flanges 5 having openings for receiving rivets for attaching the side sheets of the hopper thereto. Each of the flanges has relatively inclined portions which intersect adjacent the upper part of the frame to form an indentation for accommodating projecting portions of neighboring parts of the car body. The frame is formed with a cargo discharge opening 6 which preferably is rectangular in shape, thereby providing on opposite sides of the opening generally triangular downwardly tapering frame portions 7 intervening between said discharge opening and the respective hopper side sheets 2.

By this means increased strength and stiffness against distortion, especially toward the

upper end of the door opening, are imparted to the hopper. In order to reinforce the lower part of the door frame the latter is preferably provided with a flange 8 which passes 5 under the door opening and extends upwardly a short distance at opposite sides of the frame, as indicated at 9. The provision of the flanged portions 9 serves to reinforce the lower corners of the discharge opening 6, as 10 will be readily understood.

Formed on the frame 4 and bordering the car door discharge opening are outwardly projecting flanges for cooperating with flanges upon the door to form a seal against 15 the escape of fine lading. These flanges preferably completely define the discharge opening, the uppermost flange 10 projecting outwardly a somewhat less distance than the lower flange 11 and the two side flanges 12, 20 12 being tapered so as to increase in height toward the lower edge of the opening. The hinged door 13 for closing the hopper discharge opening is of rectangular form and may advantageously be of the pressed sheet 25 metal type so as to provide inwardly extending marginal flanges 14, 15 and 16 which not only stiffen the door but also cooperate with the flanges 10, 11 and 12 of the door frame to prevent the escape of fine lading. Suitable 30 means are provided for hinging the door, such means preferably consisting of hinge members 17 overlying the outer face of the door and riveted thereto adjacent the upper corners of the latter. The upper ends of 35 these hinge members extend between spaced hinge lugs 18 with which the door frame is integrally provided above the cargo opening. The hinge pins 19 pass through corresponding openings in the hinge members 17 and 18, thus securing the door to the frame member 4. The upper end of the frame above the hinge lugs may advantageously be fashioned with an outwardly projecting flange 20 adapted to permit said frame to be secured 40 at its upper end to a neighboring portion of the car body, and this flange also serves as a guard or protection to the hinge lugs. The side flanges 5 of the door frame unit preferably overlie the side sheets 2 of the hopper 45 instead of extending between the latter, as such a construction permits the frame to be formed with an integral bracket 21 conveniently providing for the mounting of the door locking means. In the present instance 50 two such brackets 21 are illustrated, one on each side of the hopper. They are of a form suitable for permitting the use of a pivoted door supporting hook 22 which cooperates in a well known manner with a bracket or arm 55 23 secured to the door.

I claim:—

1. Hopper car construction comprising a hopper having an inclined bottom, said hopper being provided with inclined sides extending at an angle to each other and having

a substantially rectangular discharge opening, and a substantially rectangular door for closing said opening.

2. Hopper car construction comprising a hopper having an inclined bottom and provided with sides extending at an angle to each other, said hopper being formed with a discharge opening whose marginal edges adjacent the sides of the hopper are substantially parallel, each of said marginal edges 75 extending at an angle with respect to the adjacent side of said hopper and a door for closing said discharge opening.

3. Hopper car construction comprising a hopper having an inclined bottom and provided with sides extending at an oblique angle 80 to the vertical, said hopper being formed with a discharge opening of substantially uniform width throughout, and a hinged rectangular door for closing said opening.

4. Hopper car construction comprising a hopper having an inclined bottom and provided with downwardly converging sides, said hopper being formed with a discharge opening whose lateral marginal edges are 90 substantially parallel, each of said marginal edges converging downwardly with respect to the adjacent side of said hopper, and a door for closing said opening.

5. Hopper car construction comprising a 95 hopper having an inclined bottom and provided with inclined downwardly converging sides and being formed with a discharge opening at its lower end, and a substantially rectangular hinged door for closing said 100 opening.

6. A car hopper door frame having a cargo discharge opening and provided with outwardly projecting sealing flanges bordering the sides and lower edge of said opening, in combination with a hinged door having inwardly projecting sealing flanges adapted to 105 cooperate with the corresponding flanges of said frame.

7. A car hopper door frame having a cargo discharge opening and provided with outwardly projecting sealing flanges adjacent the sides and lower edge of said opening, said flanges at the sides of the opening being increased in height toward the lower edge of said opening, in combination with a hinged door having inwardly projecting sealing flanges for co-operating with said flanges of 115 the frame.

8. A hopper car door frame having a rectangular discharge opening, said frame being provided with sealing flanges bordering said opening and being further provided on opposite sides of said opening with rigidly connected portions of generally triangular form 120 to which the side sheets of the car hopper are adapted to be attached, in combination with a hinged rectangular door for closing said opening, said door having flanges adapted to overlap the sealing flanges of the door frame 125 130.

to prevent the escape of lading, the overlapping portions of corresponding parts of the respective flanges being less at the hinged edge of the door than at the opposite free edge thereof.

9. A unitary hopper car door frame of substantially trapezoidal form having a rectangular cargo discharge opening therein, in combination with a hinged rectangular door for closing said opening, the latter being fashioned with inwardly projecting flanges overlapping portions of the door frame above and below the opening thereof, the overlapped portion of the door frame below the opening being greater than the overlapped portion above the opening.

10. A hopper car door frame of substantially trapezoidal form having a rectangular cargo discharge opening and provided with outwardly extending sealing flanges adjacent said opening, in combination with a hinged rectangular door for closing said opening, said door being provided with inwardly extending sealing flanges for cooperating with the sealing flanges of the frame, the latter being of greatest depth at points remote from the hinged edge of the door.

11. A hopper car door frame of substantially trapezoidal form having a rectangular cargo discharge opening therein, said frame being provided with outwardly extending sealing flanges bordering said opening and with oppositely disposed flanges for attaching the side sheets of the hopper to the frame, in combination with a hinged rectangular door having inwardly extending marginal flanges for cooperating with the sealing flanges of the frame.

12. A unitary hopper car door frame of substantially trapezoidal form having a rectangular discharge opening therein and provided with means for hinging thereto a door for closing said opening.

13. A hopper car door frame constructed as an integral unit and provided with a rectangular discharge opening, said frame having oppositely disposed flanges for the attachment of hopper side plates and being provided with outwardly projecting sealing flanges adjacent said opening, said last named flanges being adapted to cooperate with a door for closing said opening.

14. A hopper car door frame constructed as an integral unit and having a substantially rectangular discharge opening therein, said frame being provided with an inclined flange for forming a connection with the inclined side sheet of a car hopper, the portion of said frame which is between said flange and said opening being of general triangular form.

15. A hopper car door frame constructed as a unit and having a substantially rectangular discharge opening, said frame being provided on opposite sides of said opening with flanges for the attachment of the side sheets

of the car hopper and being formed below said opening with a downwardly extending stiffening flange and above said opening with means enabling the frame to be secured to a portion of the car body.

16. A hopper car door frame constructed as an integral unit and having a substantially rectangular discharge opening, said frame being formed with oppositely disposed flanges for the attachment of the side sheets of a car hopper and having sealing flanges adjacent the sides and lower edge of the discharge opening and being provided above said opening with a flange adapted to permit said frame to be secured to a portion of the car body.

17. A hopper car door frame constructed as a single unit and having a substantially rectangular discharge opening therein, said frame being provided with flanges for the attachment of the side sheets of the car hopper, one of said flanges being fashioned with an integral bracket adapted to form a mounting for a pivoted door supporting hook.

18. A hopper car door frame having a rectangular discharge opening, said frame being flanged for the attachment of the side sheets of the hopper and having means disposed above said opening for hinging a door to said frame and being provided above said means with a flange.

19. A unitary hopper car door frame having a lading discharge opening and being provided on opposite sides of said opening with flanges for the attachment of the side sheets of a car hopper, one of said flanges having relatively inclined portions forming an indentation to accommodate a neighboring portion of the car body.

20. A unitary hopper car door frame having a lading discharge opening, the opposite edges of said frame being indented to accommodate neighboring portions of the car body.

21. A hopper car construction involving a hopper having an inclined bottom and inclined downwardly converging sides and being formed at its lower end with a lading discharge opening, each of said downwardly converging sides having relatively inclined intersecting portions forming an indentation for accommodating projecting portions of neighboring parts of the car body.

22. A hopper car door frame constructed as a unit and having a substantially rectangular discharge opening, said frame being integrally provided on opposite sides with brackets adapted to form mountings for pivoted door supporting hooks, the lower portion of said frame being fashioned with a reinforcing flange extending beneath the door opening and merging into said brackets.

23. A unitary hopper car door frame having a lading discharge opening and provided with outwardly projecting sealing flanges adjacent said opening and with oppositely pro-

jecting flanges for attaching the side sheets of a hopper to the frame, portions of said attaching flanges terminating in a stiffening flange disposed in a plane substantially normal thereto.

24. A hopper car door frame having a discharge opening, in combination with a hinged door for closing said opening, said door having flanges for overlapping portions of the door frame bordering said opening to prevent the escape of lading, the overlapped portion of the door frame below the opening being greater than the overlapped portion thereof above the opening.
- 15 25. A hopper car door frame having a lading discharge opening and provided with outwardly projecting sealing flanges bordering said opening, in combination with a hinged door for closing the latter, said door 20 being provided with flanges for overlapping

the said flanges of the door frame to prevent the escape of lading, the overlapping portions of corresponding parts of the respective flanges being less at the hinged edge of the door than at the opposite free edge thereof. 25

26. A hopper car door frame having a lading discharge opening and provided with outwardly projecting sealing flanges bordering the said opening, in combination with a hinged door having inwardly projecting 30 flanges for overlapping the flanges of the frame to prevent the escape of lading, the flange of the door frame adjacent the free edge of the door projecting outwardly to a greater extent than the flange of the door frame adjacent the opposite hinged edge of the door.

In testimony whereof I affix my signature.

WILLIAM E. WINE.
